UNITED STATES PATENT OFFICE.

FRANK E. KEYES, OF NEW YORK, N. Y.

FEED-WATER HEATER.

SPECIFICATION forming part of Letters Patent No. 781,005, dated January 31, 1905.

Application filed September 29, 1903. Serial No. 175,070.

To all whom it may concern:

Be it known that I, FRANK E. KEYES, a resident of New York, in the county of New York and State of New York, have invented certain new and useful Improvements in Feed-Water Heaters; and I do hereby declare the following to be a full, clear, and exact description of the invention, such as will enable others skilled in the art to which it appertains to make and use the same.

My invention relates to an improved boiler-feed, and more particularly to means for heating feed-water and supplying the same to the boiler, the object of the invention being to provide simple and efficient means whereby the water will be brought to the boiling-point before it is let into the boiler.

A further object is to avoid the use of a pump, inspirator, or injector and to avoid all use of exhaust-steam from an engine or pump, and thus obviate the damaging effects produced in the boiler by oil and grease coming from the exhaust-steam.

A further object is to produce a water-heater and feed for steam-boilers which shall be simple in construction, sure and accurate in operation, and which shall be effectual in all respects in the performance of its functions.

With these objects in view the invention consists in certain novel features of construction and combinations and arrangements of parts, as hereinafter set forth, and pointed out in the claims.

The accompanying drawing is an elevation showing an embodiment of my invention.

A represents a steam-boiler, and 1 the steam-dome thereon. Supported upon and in close proximity to the boiler and its steam-dome, by means of brackets 2, is a tank 3, which constitutes the water-heater. A coupling 4, having two ducts 5 and 6, is located over one end of the tank or heater 3, the ducts 5, 6 merging at their lower ends and both communicating with a short pipe-section 7, extending into the top of the tank in proximity to the end thereof nearest the steam-dome of the boiler. A pipe 8 communicates at one end with the straight duct 5 in the coupling 4 and at its other end with a supply-tank 9, (or a hydrant,) said pipe being provided at a point in proximity to the

coupling 4 with a valve 10. A pipe 11 communicates at one end with the lateral duct 6 in coupling 4 and at the other end with the steam-dome of the boiler, this pipe being provided with a valve at 12. At the far end of the tank a pipe 13 communicates therewith, and the other end of this pipe projects into the end of the boiler to supply water to the latter from the tank 3. A valve 14 is located in the pipe 13 for the purpose of controlling the flow of water into the boiler. A vent 15, having a valve 16, communicates with the top of the tank at the end thereof farthest from the inlet for water and steam, and this vent communicates, by means of a pipe 17, with the supply-tank or hydrant, so that steam passing from the tank through said vent can be utilized to heat the water in the supply-tank before said water enters the tank or heater 3.

To permit dirt which may accumulate in the tank or heater 3 to be washed out, I provide a pipe 18, which communicates at its upper end with the bottom of the tank or heater 3 and at its other end with a sewer or other place of discharge and is provided at a suitable point with a cock 19.

With the construction and arrangements of parts above described the water will be brought to the boiling-point in the tank 3. The water from the supply-tank or hydrant will be made to enter the tank 3 simultaneously with the steam, the steam entering through the pipe 11 and coupling 4 also serving to assist the flow of water through pipe 8 and duct 5 of coupling 4 into the tank 3. Thus when the vent 15 and pipe 17 are open water from the supply-tank will be injected into the tank or heater 3 by the steam from the steam-dome passing through the pipe 11.

Various slight changes might be made in the details of construction of my invention without departing from the spirit thereof or limiting its scope, and hence I do not wish to limit myself to the precise details herein set forth.

Having fully described my invention, what I claim as new, and desire to secure by Letters Patent, is—

1. The combination with a boiler, a tank or heater, a pipe for conducting water therefrom to the boiler, and a source of water-supply, of

a pipe connecting the source of water-supply with the tank or heater, a pipe connecting the tank or heater with the steam-dome of the boiler, and a pipe connecting the top of the tank or heater with the source of water-supply.

2. The combination with a boiler, a tank or heater, a pipe for conducting water therefrom to the boiler, and a source of water-supply, of a coupling communicating with the tank or heater, said coupling having a vertical duct and an inclined duct, a pipe connecting the vertical duct with the source of water-supply,

a pipe connecting the inclined duct with the steam-dome of the boiler, and a pipe connecting the top of the tank or heater with the source of water-supply.

In testimony whereof I have signed this specification in the presence of two subscribing witnesses.

FRANK E. KEYES.
